Primary Examiner — T. Chase Nelson*Assistant Examiner* — Mark Cavanna(74) *Attorney, Agent, or Firm* — Finnegan, Henderson, Farabow, Garrett & Dunner, LLP**CLAIM**

The ornamental design for an electrode headset, as shown and described.

DESCRIPTION

FIG. 1 is a front right perspective view of a first embodiment of an electrode headset showing our new design;

FIG. 2 is a front elevation view thereof;

FIG. 3 is a left side view thereof;

FIG. 4 is a rear elevation view thereof;

FIG. 5 is a top plan view thereof;

FIG. 6 is a bottom view thereof;

FIG. 7 is a front right perspective view thereof, with the electrode headset shown in a flexed position showing our new design;

FIG. 8 is a front elevation view of FIG. 7;

FIG. 9 is a left side view of FIG. 7;

FIG. 10 is a rear elevation view of FIG. 7;

FIG. 11 is a top plan view of FIG. 7; and,

FIG. 12 is a bottom view of FIG. 7.

The portions depicted in broken lines are environment and the elements depicted in broken lines form no part of the claimed design.

1 Claim, 10 Drawing Sheets(56)
